UNITED STATES PATENT OFFICE.

AXEL KILSTROM, OF PROVIDENCE, RHODE ISLAND.

ERASER FOR LEAD-PENCILS.

1,104,514.

Specification of Letters Patent. Patented July 21, 1914.

Application filed January 5, 1914. Serial No. 810,442.

To all whom it may concern:

Be it known that I, AXEL KILSTROM, a citizen of the United States, residing at Providence, in the county of Providence and State of Rhode Island, have invented certain new and useful Improvements in Erasers for Lead-Pencils; and I do declare the following to be a full, clear, and exact description of the invention, such as will enable others skilled in the art to which it appertains to make and use the same.

This invention relates to improvements in erasers and more particularly to those which are primarily adapted for use in connection with the end of a pencil.

The primary object of the invention is to produce a simply constructed device of this character having means whereby when the eraser has worn a considerable extent, the same may be further projected from its retaining sleeve so that a new working area is provided.

A secondary object is to provide means for automatically securing the eraser in any one of its adjusted positions.

With the above objects in view, the invention resides in certain novel features of construction and combination herein described and claimed and shown in the drawings wherein—

Figure 1 is a side elevation of a pencil showing my improved eraser applied thereto; Fig. 2 is a vertical longitudinal section thereof on the line 2—2 of Fig. 1; Fig. 3 is a horizontal section on the line 3—3 of Fig. 2, the eraser having been projected to its greatest extent; Fig. 4 is a detail perspective view of the element to which the eraser is secured and which is slidably mounted within the guide sleeve; and Fig. 5 is a bottom plan view thereof.

In the accompanying drawings, I have shown my improved attachment in the form of a tubular guide 1 having a longitudinal slot 2 in its outermost portion, a plurality of notches 3 opening into said slot and thus forming teeth 4. The inner end of the tubular guide 1 is adapted to fit snugly over the inactive end of a pencil P and is secured in place by means of studs 5 struck inwardly from the inner end of said guide. The outer end of the guide 1 is provided with a plurality of inwardly extending studs 6 for a purpose to appear.

Slidably mounted within the guide 1 is a substantially square plate 7 having an in-

tegral neck 8 projecting from one corner thereof through the slot 2, said neck being provided with an upwardly curved operating knob 9. The sides of the plate 7 are provided with integral gripping tongs 10 which are curved upwardly and embedded into the sides of the inner end of the eraser 11. The inner face of the plate 7 is notched as at 12 to produce a shoulder in which the upper end of a coil spring 13 is seated, said spring being under longitudinal and torsional tension and having its lower end seated in a notch 14 formed in the adjacent end of the pencil P. With the spring thus arranged, the tendency thereof is to rotate the plate 7 and cause its neck 8 to engage one of the notches 3 which communicate with the slot 2. When however, the eraser 11 is turned to disengage the neck 8 from one of said notches, the longitudinal tension of the spring will be exerted and the plate 7 and the eraser 11 will be projected beyond the outer end of the guide 1 a suitable distance, after which the eraser may be released and the torsional tension of the spring 13 will again engage the neck 8 with one of the notches 3.

When the major part of the eraser 11 has been used, it will be understood that the plate 7 will stand beneath the studs 6 at the top of the guide 1, and through the above mentioned means, the neck 8 will be seated in the uppermost notch 3. When in this position the corners 7' of the plate 7 will lie directly beneath said studs. When now it is desired to remove the plate 7 for the purpose of applying a new eraser, it is absolutely necessary to turn said plate so that its neck rests within the upper end of the slot 2, which upper end is enlarged as at 2' for this purpose. This action, when imparted to the plate 7, will turn the corners 7' of the plate to such an extent as to bring them out of contact with the studs 6. The entire plate may now be rocked as shown in dotted lines in Fig. 2 upon which action the neck 8 and the knob 9 will be disengaged from the slot 2 and the upper notch 3 and thus the plate may be readily removed for the above mentioned purpose.

From the above described construction, it will be seen that I have produced a very simple and efficient attachment which may be applied to pencils of ordinary construction and which will be very useful. It is to be understood however, that I do not

wish to be limited to the application of my invention to a pencil since it will be obvious that it would operate to equal advantage when secured to any suitable form of handle.

5 Having thus described my invention, what I claim as new and desire to secure by Letters-Patent is:

1. A device of the character described comprising a tubular guide formed with a longitudinal slot and a plurality of transverse notches opening into said slot, a substantially polygonal plate slidable within said guide, an integral neck on one corner of said plate, said neck passing through said slot, an operating head formed on the outer end of said neck, a cylindrical eraser resting on said plate, integral tongs formed on the edges of said plate and bent into the sides of said eraser, a coil spring for forcing said plate normally outward and a plurality of projections struck inwardly from the free end of said guide for limiting the outward movement of said plate.
- 10
- 15
- 20

2. The combination with a pencil, of a tubular guide secured to and incasing one end thereof, said guide being formed with a longitudinal slot and a plurality of notches opening into said slot, a slide within said guide, a shoulder on the inner side of said slide, an operating knob on said slide and passing through said slot, a cylindrical eraser carried by said slide, a shoulder on the incased end of said pencil, and a coil spring disposed between said slide and said pencil and in contact with said shoulders, said spring being under longitudinal and torsional tension whereby said knob is retained yieldingly within one of said notches for the purpose set forth.

25 30 35 In testimony whereof I have hereunto set my hand in presence of two subscribing witnesses.

AXEL KILSTROM.
